T. VEITCH

VACUUM FUEL FEEDING DEVICE FOR INTERNAL COMBUSTION ENGINES

Filed June 27, 1925

UNITED STATES PATENT OFFICE.

THOMAS VEITCH, OF BRADLEY BEACH, NEW JERSEY, ASSIGNOR, BY DIRECT AND MESNE ASSIGNMENTS, OF FORTY PER CENT TO PAUL M. ABRAHAMS AND TWENTY PER CENT TO ISRAEL G. CASS, BOTH OF NEW YORK, N. Y.

VACUUM FUEL-FEEDING DEVICE FOR INTERNAL-COMBUSTION ENGINES.

Application filed June 27, 1925. Serial No. 39,893.

My invention relates to improvements in vacuum fuel feeding devices for internal combustion engines in which the vacuum raises the fuel intermittently from a tank below the level of the engine carbureter to a chamber controlled by a float and valve, the fuel passing from this chamber through a check valve to an atmospherically vented lower chamber and thence by gravity to the carbureter; and the objects of my improvements are, first, to provide a cheap, substantial and readily constructed double chamber or tank; second, to provide a single cover containing all the connections and mechanism for unit assembly; third, to provide a rapid clamping means for attaching to and removing the cover from the upper chamber for ease in assembling, cleaning and inspection, fourth, to provide a vacuum and vent valve that will not wear or stick and that has large ports to insure the rapid filling and emptying of the vacuum chamber; fifth, to provide a valve trip mechanism that is positive in its action and comprises a minimum number of parts and that will operate with a small volume float acting through a large angular range; sixth, to provide an outlet valve from the upper or vacuum chamber into the lower vented one that will open and close promptly with the least difference of head, that will give an unrestricted flow when open and that will discharge sediment and all extraneous matter entering the vacuum chamber with the fuel.

The several objects of my invention outlined above together with others that will shortly appear are now to be described and are illustrated in the accompanying drawings forming a part of this specification.

Fig. 1 is a vertical section of one form of a containing vacuum fuel tank, my invention showing the upper or vacuum chamber and the lower or supply chamber or tank; Fig. 2 is a part section on the line A—A taken in a plane at right angles to the section plane of Fig. 1 and shows the vacuum valve, trip mechanism and float; Fig. 3 is an enlarged sectional view of the valve and trip mechanism in the same plane as Fig. 1 but with the valve and trip mechanism shown in a differ-

ent position; Fig. 4 is a partial sectional view of a modified form of vacuum valve that may be used with the regular trip mechanism of my invention; and Fig. 5 is a partial section of the tank and cover showing a means of securing the cover by an interrupted screw or multiple sectional thread.

Similar characters of reference are used to denote the same parts throughout the several views.

Referring to the drawings in detail and particularly to Fig. 1, numeral 1 represents the outer tank or supply chamber. I prefer to make this of sheet metal seamed and provided at the top 2 with a wired edge for strength and a finished seating. This chamber may be vented to the atmosphere in several ways, the way I prefer is to provide grooves across the top of the wired edge. The bottom 3 of this chamber is preferably seamed to the side wall and is provided with an outlet flange 4 and a pipe 5 leading to the carbureter of the internal combustion engine. The vacuum chamber 6 is about half the height of the supply chamber and is made of such outside diameter that it fits loosely into the supply chamber. It has a wired edge 7 that sets on top of edge 2 and it is thus held suspended at the top of chamber 1. It is not necessary that the joint between these two chambers be air-tight, so no gasket is shown although one may be used.

The outlet valve for permitting the liquid fuel drawn into the upper or vacuum chamber 6 to flow by gravity into the supply chamber 8 is composed of a seat 9 preferably formed integral with the base 10 secured to the bottom of chamber 6. The valve head 11 is rounded into spherical contour so that it will seat tightly, although by reason of the fact that the valve is spherical and loosely articulated, it will assume a slightly different position each time it is seated. The shape is used because it permits a free discharge of liquid and offers no lodging for sediment. Another advantage for the shape is that it closes promptly due to increased pressure on the concave under surface when any liquid tends to pass upward through the valve. The valve head 11 is supported on a center

stud 12 passing loosely through a hole in the end of a bar 13 pivoted in the base lugs 14. The bar 13 is counterbalanced by a weight 15^a just heavy enough to hold the valve closed. The advantage of this construction is that when the valve opens it opens fully and promptly, as its resistance does not increase with the increase of opening. The cover 15 for the vacuum chamber I prefer to form from sheet metal in a press, giving it a raised angular rim 16 for mechanical strength and at the same time use the recess to hold the gasket 17 of cork or other elastic material not affected by the fuel.

To fill the vacuum chamber with fuel from the main tank at a lower level requires a piped connection between the vacuum chamber and the bottom of the main tank. The pipe leading to the main tank is shown at 18. This is screwed into a flanged fitting 19 which in turn is screwed into a recess 20 formed integral with the cover and holding at its lower end a screen 21 to prevent large particles of foreign material entering the vacuum chamber.

The vacuum and vent valve seat I prefer to form from a single fitting 22 of hexagonal or square material, tapped at its upper end 23 to take the pipe 24 connecting with the inlet manifold of the internal combustion engine. The lower end 25 of this fitting is threaded so that the nut 26 may serve to hold it in place in the cover 15. It is preferably so located that a flat side 27 will fit against the inside of the rim 16 and so prevent its turning. The lower end of 22 is cut into a V shape with the sides forming an angle of about 90° for best results. These sides form the valve seats and through one is drilled the vacuum port 28 connecting with the tapped opening 23 and through the other is drilled the vent port 29 passing upward and then at right angle through the side of the fitting 22 to the outer air. The valve 30 for alternately opening and closing these ports is also V shaped and is formed preferably from a short cylinder with two sides cut at an angle to each other, the included angle being a few degrees less than the angle formed by the valve seats. The V edge of the valve is adapted to rest in the bottom of the V groove of the seat and thus permit the valve to rock back and forth from one seat to the other without any sliding friction and therefore no wear. There is no wear occasioned by the valve seating as direct contacts are made and broken without any sliding action. The frame for holding the valve trip mechanism is shown at 31 and is an E shaped strip of sheet metal or punching. The base 32 for supporting it has a hole that fits over the end 25 and is held to the cover 15 by the nut 26 that also secures the valve seat fitting in place. This nut 26 is made thick enough to embrace the lower end of the valve 30 and so retain it in

alignment with the seat (see Fig. 2). The lower end 33 of the E shaped support is bent upward at 34 forming two knife edge bearings one at each side for the float arm 35, the two sides of which have V shaped notches 36-36 resting on the knife edge bearings 34-34 and upon which the float arm is adapted to rock back and forth on these as the float arm is raised and lowered by the float 37 secured between the arms 35-35 by the rivet 38. The float arms 35 are held together by a bridge piece 39 and this has a tongue 40 that is bent into a V shape and aligned with the edges 34-34. The float arm is held to its bearings as is also the valve 30 by two toggle members or levers 41 and 42. Toggle lever 41 is a flat strip of metal and has a broad knife edge that rests in a V groove 43 in the valve 30 and the toggle 42 is a Y shaped standing, the stem of which passes through a slot in the tongue 40 and has a helical compression spring 44 surrounding it and pressing against the head of the Y and against the tongue 40. The V of the Y head forms a bearing 45 for the free end of the toggle lever 41 and forces that member toward the valve 30 holding it to its seat. The rocking angular movement of the toggle lever 41 is limited by stops 46 and 47 which also act as fulcra to enable the toggle lever 41 to forcibly rock the valve 30 from the contact with one seat into contact with the other, as it moves from contact with fulcrum 46 into contact with fulcrum 47. The mechanism that initiates the movement of the toggle lever 41 comprises forked ends or teeth projecting from the float arm 35 opposite the V notches 36-36. These fork teeth embrace the extended sides 49-49 of the toggle lever 41 and the surfaces of the fork teeth 50 and 51 that are adapted to coact with the toggle sides 49-49 are flared outwardly generally resembling the contour of gear teeth, for the purpose which will appear hereafter.

The clamp with which I secure the cover 15 to the double chambered tank comprises a metal bar 52 with its ends bent into hook forms 53 and provided with two thumb or other type of screws 54. The hooks are adapted to fit under the wired edge of the supply chamber or tank 1 on diametrically opposite sides and when the screws are tightened down against the cover rim 16, the vacuum chamber is made air-tight and the both tanks are securely held in position. The screws may be locked against loosening by a wire passed through holes 55 in each. This clamp furnishes a rapid and convenient means of assembly and also of inspection and cleaning, as unions are provided at or near the vacuum and gasoline fittings 19 and 22. I do not limit myself to the use of two screws in the clamp as a single screw at the center may be used as may also a cam pressing means, without departing from my invention.

A desirable means of securing the cover to the vacuum chamber is shown at Fig. 5 and consists in making the outer rim of the cover 15^b of great enough depth to have a screw 5 thread 60 indented in its side or to have a series of short thread sections so arranged that they coat with a similar set of thread sections 61-61 pressed outward in the wall of the tank 1^a which for the purpose, has its 10 wired edge 2^a on the inside as shown. This construction permits the cover to be removed by loosening the pipe connecting unions and giving the cover a partial turn.

I will now proceed to describe the operation 15 of my vacuum fuel feeding device. Assuming first that the cover has been tightly clamped in place and that the various pipes are properly connected. The engine is first started either by the fuel in the carbureter 20 or by the crank or starting means usually provided, this produces a partial vacuum in the inlet manifold and as the vacuum chamber 6 is empty the float 37 and valve mechanism will occupy the position shown in Fig. 1 of 25 the drawings. A partial vacuum will be produced in chamber 6 and this will immediately start to fill with fuel through the pipe 18. As the chamber fills the float 37 rises and the lower position of the tooth surface of 30 50 contacts with 49 and presses the toggle 41 to the right until the two toggle members are in line; at which time the point of contact between the surface 50 and 49 has moved to 35 near the outer end of 50 and the float is near the upper end of its travel. A little further upward movement of the float presses the toggle levers slightly beyond the straight alignment and they snap over to the right until 40 41 comes into contact with fulcrum 47, then the spring pressure of 44 together with the inertia of both toggle members is transferred into a push, to the left, of joint 43 and to the upper part of the valve 30, causing it to rock to the left and to close the vacuum 45 port 28 and to open the vent port 29. As soon as this occurs the interior partial vacuum of the chamber 6 is equalized to atmospheric pressure ad the valve 11 opens permitting the fuel in chamber 6 to be discharged 50 by gravity into the tank 1 and from here flowing through the pipe 5 to the carbureter.

As the chamber 6 empties and the float descends the same action but in a reverse direction takes place. The lower surface of 55 51 contacts and moves the toggle lever 41 to the left. This movement continues until the toggle train is unbalanced by passing the center of alignment, then the center 45 snaps over to the left, toggle 41 strikes the fulcrum 46 and the valve 30 is forcibly rocked to the right into the position it occupied at the beginning and as shown in Fig. 1. The action of filling and emptying will continue until the supply chamber becomes filled. The float 60 cannot then reach its lowermost position to

70 snap the valve to the filling position, but as soon as liquid flows from the lower chamber and permits the float to descend, the valve will open the vacuum port 28 and the filling action will recommence.

In Fig. 3 the float 35 and the fork teeth are 75 shown in the position where the toggle members have just snapped the valve over to the vented position. The advantage of the changing leverage ratio is illustrated in this figure and shows that, at the end of the float travel either up or down the contact point between the fork teeth of the float arm and the toggle lever 41 is at the extreme end of the gear tooth surface and at the point of least leverage ratio, whereas at the beginning of the float travel the contact is at the point of greatest ratio and the resistance to motion of the toggle train is in the same ratio; that is, greatest at the start and practically nothing at the point of snap over. This means 80 that the float does not submerge unduly at the beginning before it gains enough power to start the toggle movement and then bob upward or down suddenly against the decreasing resistance, but in my invention it starts moving steadily and furnishing power to the toggles until the point of snap over is reached at which time it is almost at its end of travel, 85 is doing very little work so is floating near its normal submergence. A still further gain secured by the changing leverage ratio of the float arm is that it enables a much smaller float to be used and because the float 90 does not suddenly bob up or drop down a greater effective angular travel of the arm may be used. The small volume float permits cork or other solid light material float to be used and also leaves a greater capacity in the 95 vacuum chamber for the charge of liquid fuel. The greater quantity of liquid handled per float oscillation means less wear on the mechanism and longer life, at the same time the more regular even oscillation of the 100 float reduces to a minimum all shock and strains on the mechanism.

I wish to call attention to another very important feature of my valve and trip mechanism; that it insures the valve being held firmly in contact with either valve seat up to the very instant of snap over. In Fig. 3 105 it will be noted that the valve is being held to the left hand or vacuum port seat by the pressure of the spring acting on toggle 41 which tends to turn as a lever about the fulcrum 47. As the float arm moves down the toggle train is brought to the position of 41^a and 42^a (shown dotted) in which position it 110 is ready to snap over to the other side, but pressure even now is tending to hold the valve firmly against the same valve seat and this pressure will remain until 41^a has come 115 into contact with the fulcrum 46. I have been referring to the trip mechanism as a two membered toggle train whereas in fact it 120

is a three membered train, the center line of the valve, from the V edge to point 43 being the third member. The trip mechanism will not operate without this third member.

5 Fig. 4 shows a modified form of valve but using the same toggle trip mechanism. 22^a is the valve fitting, 28^a the vacuum port and 29^a the vent port. The valve seat 53 is a plane and the valve 30^a has an operating face 10 a few degrees less than 180°. A notch in the center of the valve seat receives a projection 52 on the valve and prevents it from sliding. 15 41 is one toggle member and 42 the other, 44 being the spring while 46 and 47 are the fulcrum abutments. No other parts of mechanism are shown as the action is the same as in the preferred form just described.

While I have shown and described in detail the best form for applying my invention 20 now known to me, I do not therefore, intend to limit myself to the specific details of such form, but desire to cover the principle of my invention broadly in any form in which it may be embodied.

25 Having thus described my invention, what I claim as new, and desire to secure by Letters Patent, is:

1. In a vacuum fuel feed apparatus comprising a suction chamber, a valve seat having a V-shape, a port in each side of the V and a wedge-shaped valve rocking within said V, and toggle means for holding said valve against said seat to retain said valve against one or the other of said ports.

35 2. In a vacuum fuel feed apparatus, comprising an inlet port for fuel, a valve seat having vacuum and venting ports therein, a rocker valve cooperating at all times with one of said ports, toggle means associated with 40 said rocker valve, and float operable means for cooperating with said toggle means for actuating said valve, and limiting stops for controlling the extreme movement in either direction of said valve.

45 3. In a vacuum fuel feed apparatus, comprising a suction chamber, of fuel inlet therein, a valve seat having a plurality of ports therein, a valve movable in said seat, a plurality of toggle arms for actuating said valve, means for limiting the movement of said toggle arms, and float operable means for actuating said toggle arms.

55 4. In a vacuum fuel apparatus, comprising a suction chamber, a valve seat having ports communicating with said suction chamber, a valve adapted to rock on said valve seat for cooperating with said ports, toggle means associated with said valve for operating the same, limiting means for determining the movement of said toggle means in either direction, and float means for actuating said toggles.

60 5. In a vacuum fuel feed apparatus, comprising suction chamber, a valve seat having ports communicating with a source of

suction and with the atmosphere, a valve adapted to cooperate with said valve seat for controlling the opening and closing of said ports, toggle means associated with said valve, tension means for maintaining the toggle means in contact with said valve, and buoyancy operable means for initiating the toggle movement.

6. In a vacuum fuel feed apparatus, comprising a suction chamber, a valve seat having ports communicating with a source of suction and with the atmosphere, a valve adapted to cooperate with said valve seat for controlling the opening and closing of said ports, toggle means associated with said valve, tension means for maintaining the toggle means in contact with said valve, buoyancy operable means for initiating the toggle movement, and a fulcrum cooperating with said toggle means for determining the direction of movement of said valve.

7. In a vacuum fuel feed apparatus, the combination with a supply chamber, of a suction chamber cooperating therewith, a valve seat having a plurality of ports communicating with the suction chamber, a valve adapted to rock on the valve seat and toggle means for controlling the movement of said valve.

8. In a vacuum fuel feed apparatus, the combination with an upper suction chamber, and a lower supply chamber, a valve seat in said suction chamber having ports communicating with suction means and with the atmosphere, a V shaped valve located in said suction chamber and means for actuating said valve in rocking engagement with said valve seat whereby to intermittently close the respective ports in said valve seat, and means operable by buoyancy for actuating said valve.

9. In a vacuum fuel feed apparatus, the combination with an upper suction chamber, and a lower supply chamber, a valve seat in said suction chamber having ports communicating with suction means and with the atmosphere, a V shaped valve located in said suction chamber and means for actuating said valve in rocking engagement with said valve seat whereby to intermittently close the respective ports in said valve seat, a toggle lever in rocking engagement with the valve, abutments for limiting the rocking movement of said lever, and a float cooperating with the toggle lever at the extremity thereof for oscillating the same.

10. In a vacuum fuel feed apparatus, the combination with an upper suction chamber, and a lower supply chamber, a valve seat in said suction chamber having ports communicating with suction means and with the atmosphere, a V shaped valve located in said suction chamber and means for actuating said valve in rocking engagement with said valve seat, whereby to intermittently close the respective ports in said valve seat, a toggle lever

in rocking engagement with the valve, a plurality of abutments for limiting the rocking movement of said lever, a second toggle lever movable about a fixed bearing, and spring 5 pressed into jointed engagement with the movable end of said first toggle lever, an arm oscillatable about the fixed bearing and having a fork adapted to engage the movable end at the first section of toggle lever, and a 10 float cooperating with said arm for causing it to oscillate as fuel enters and leaves the suction chamber.

11. In a vacuum fuel feed apparatus, the combination with a supply chamber, of a suction chamber associated therewith, and means 15 for filling and venting said suction chamber, said means consisting of a toggle operated rocker arm cooperating with a valve seat containing a plurality of ports and gravity oper- 20 able means for discharging said fuel from

said suction chamber, into said supply chamber.

12. In a vacuum fuel feed apparatus, the combination of a vacuum chamber, and a fuel inlet therefor, a vacuum conduit for connecting said chamber to an intake, a vent conduit for connecting said chamber with the outer air, a valve for closing each of said conduits, means for exerting a constant pressure on said valves to hold the same in open and in closed 25 positions, means for operating said valves adapted simultaneously to close one valve with the opening of the other, a float and means for connecting said float with said valve-operating means including a lost motion 30 device whereby as said valve approaches its extreme of travel in either direction, it will operate said valve operation mechanism through said lost motion device.

THOMAS VEITCH.
